UNITED STATES PATENT OFFICE.

JOSEPH E. WOLL, OF PITTSBURG, PENNSYLVANIA, ASSIGNOR OF ONE-HALF
TO HENRY J. THOMA AND WILLIAM M. McCOMBS, OF SAME PLACE.

MACHINE FOR GRINDING SHOVEL-BLANKS.

SPECIFICATION forming part of Letters Patent No. 403,818, dated May 21, 1889.

Application filed March 17, 1887. Renewed March 7, 1889. Serial No. 302,389. (No model.)

To all whom it may concern:

Be it known that I, JOSEPH E. WOLL, of Pittsburgh, in the county of Allegheny and State of Pennsylvania, have invented a new and useful Improvement in Machines for Grinding Shovel-Blanks; and I do hereby declare the following to be a full, clear, and exact description thereof, reference being had to the accompanying drawings, forming part of this specification, in which—

Figure 1 is a plan view of the machine. Fig. 2 is a side view thereof. Fig. 3 is a vertical cross-section on the line xx of Fig. 2. Fig. 4 is a side elevation of the rising table. Fig. 5 is a plan view of the plate 19. Fig. 6 is a side view of the table and table-top separated from each other. Fig. 7 is a partial plan view thereof. Fig. 8 is a vertical cross-section on the line yy of Fig. 7.

Like symbols of reference indicate like parts in each.

In the drawings, (see Figs. 1 and 2,) 2 represents the fixed part or frame of the machine. Mounted on the frame 2 in suitable slide-bearings are two slide-bars, 3, which are set at an angle to each other, as shown in Fig. 1. At the rear end of the slide-bars 3 they are provided with cam yokes or heads 4, in which are fitted eccentrics 5. These eccentrics are fixed to and are driven by rotary shafts 6. The shafts 6 are driven by belts 7, extending from an overhead shaft, 8, around belt-pulleys 9. At the forward ends of the slide-bars 3 are transversely journaled rotary shafts 10, which carry emery-wheels 11 at their inner ends. The shafts 10 are driven by belts 12, which extend from the overhead shaft 8 around belt-pulleys 13 on the shafts 10. The rotation of the shaft 8 drives the eccentrics 5 and causes the slide-bars 3 to reciprocate back and forth on their slide-bearings. The emery-wheels at the ends of the shafts 3 are arranged so that they shall reciprocate with the slide-bars over the surface of a table, 14, on which the shovel-blanks are placed. In Fig. 1 I show the shovel-blank set on top of the table.

b indicates the scarf to be ground. The reciprocation of the bars 3 carries the emery-wheels back and forth over the scarf and grinds it down flush with the blank. The cams 5 are set relatively to each other, so that

they shall move the slide-bars 3 simultaneously in opposite directions, one bar moving forward while the other moves back. The construction of the table which supports the shovel-blank is shown in Fig. 2 and in the figures on the third sheet of the drawings. It consists of a vertical hollow box, 14, within which is mounted a vertical slide-bar, 15. At the base of the box 14 is a foot-lever, 16, which is pivoted at 17 and connected with the slide 15 by a link, 18. At the top of the slide 15 is a flat head-plate, 19, supported above the slide by suitable bracket-arms, 20. The table-top 21 is a flat metal plate having a central pin, 22, on its under side, which fits into a hole, 23, in the top of the plate 19. The top 21 may be turned on the pin 22 as on a pivot. The limits of its rotation are confined by stop-pins 24 on the under side of the table-top, which are arranged to engage the corners of the plate 19. (See Fig. 5.)

On top of the rotary top 21 and at the end thereof is a socket-piece, 25, having a horizontal recess, 26, to confine the shovel-strap. The shovel-blank is put on the table-top, the strap being set between two pins, 27, and inserted into the bore 25. The foot-lever 16 is then depressed so as to raise the table-top up to the level of the reciprocating emery-wheels. The cam-shafts 6 are then set in motion, so as to reciprocate the emery-wheels over the edges of the scarfs, and, if necessary, the table-top is turned on the pivot 22 during the reciprocation of the emery-wheels, so as to present the entire curved lines of the scarfs to the grinding action.

Other mechanism may be used to reciprocate the slide-bars 3 instead of the cams. For example, hand-levers may be employed, since it is necessary to impart only a slow motion to these parts.

I claim—

1. In a machine for grinding the scarfs of shovels, the combination, with a table for supporting the blank, of two rotary grinding-wheels having reciprocating bearings arranged to converge over the table, and mechanism for imparting alternate reciprocatory motion to said bearings, substantially as and for the purposes specified.

2. In a machine for grinding the scarfs of

shovels, the combination, with an oscillatory or vibratory table, of a rotary grinding-wheel, bearings therefor arranged to move in a line tangential to a circle described around the 5 pivot of the vibratory table, and mechanism for reciprocating the grinding-wheel and its bearings, substantially as and for the purposes specified.

3. In a machine for grinding the scarfs of shovels, the combination, with a horizontally-10 reciprocating grinder, of a sliding gravity or

drop table having an oscillatory shovel-bed, and a pivoted lever, by means of which the sliding table can be raised, substantially as and for the purposes specified.

In testimony whereof I have hereunto set my hand this 22d day of February, A.D. 1887.

JOSEPH E. WOLL.

Witnesses:

W. B. CORWIN,
THOMAS W. BAKEWELL.
